Primary Examiner — Carol P Rademaker(74) *Attorney, Agent, or Firm* — Kirschstein, et al.(57) **CLAIM**

The ornamental design for a bottle, as shown and described.

DESCRIPTION

FIG. 1 is a front elevational view of a bottle according to my new design, the rear elevational view being a mirror image; FIG. 2 is a top plan view thereof;

FIG. 3 is a left side elevational view thereof, the right side elevational view being a mirror image; and,

FIG. 4 is a bottom plan view thereof.

The broken lines shown in the drawings of the upper neck and pour spout portion and of the inner and outer bottom surface portions are included for the purpose of illustrating environmental structure and form no part of the claimed design.
